UNITED STATES PATENT OFFICE.

CHARLES W. SHINTON, OF BELLEVILLE, ILLINOIS.

PISTON FOR OIL-PUMP GOVERNORS.

1,073,822.

Specification of Letters Patent. Patented Sept. 23, 1913.

Application filed August 9, 1912. Serial No. 714,294.

To all whom it may concern:

Be it known that I, CHARLES W. SHINTON, a citizen of the United States, residing at Belleville, in the county of St. Clair, State 5 of Illinois, have invented certain new and useful Improvements in Pistons for Oil-Pump Governors; and I do hereby declare the following to be a full, clear, and exact description of the invention, such as will 10 enable others skilled in the art to which it appertains to make and use the same.

This invention relates to pistons for use in oil pump governors.

The object of the invention resides in the 15 provision of a piston of the character named which will effectively prevent the escape of oil from the pressure end of the cylinder to the non-pressure end thereof and therefore at all times accurately regulate the action of 20 the pump in accordance with the pressure of oil in the delivering main and reservoir.

A further object of the invention resides in the provision of a piston of the type named which will be durable, efficient in action and comparatively inexpensive to 25 manufacture.

With the above and other objects in view the invention consists in the details of construction and in the arrangement and combination 30 of parts to be hereinafter more fully described and particularly pointed out in the appended claims.

In describing the invention in detail reference will be had to the accompanying 35 drawings wherein like characters of reference denote corresponding parts in the several views, and in which—

Figure 1 is a side elevation of an oil pump governor having the improved piston associated therewith. Fig. 2 a partial longitudinal section of what is shown in Fig. 1. Fig. 3 a longitudinal section through the piston detached, and Fig. 4 a detail perspective view of the perforated disk which 45 constitutes the pressure end of the piston head.

Referring to the drawings, the improved piston is shown as comprising a piston rod 40 A, and a piston head B, the latter being 50 mounted for reciprocation in the usual cylinder C. The piston rod A extends through one end of the cylinder C and has formed thereon an annular flange 10 disposed exteriorly of the cylinder C. The end of the 55 cylinder C remote from the piston rod A is connected to the desired oil main by means

of a pipe 11 whereby the pressure of the oil entering the cylinder C through said pipe 11 will be exerted against the piston head B. Mounted on the end of the cylinder C remote from the pipe 11 is a yoke 12 of U-shape and having threaded in the bight portion thereof a tubular screw 13 provided with a hand wheel 14 at one end and a lateral flange 15 at the other end, said flange 60 being disposed between the arms of the yoke 12. The piston rod A passes through the bore of the screw 13 and is operatively connected to the throttle 16 which controls the passage of steam to the oil pump. Encircling the piston rod A and having one end bearing against the flange 10 and the other end against the flange 15 is a spring 17, said spring constantly tending to force the piston head B toward the pipe 11 and the tension 65 of said spring being readily regulated by the manipulation of the screw 13 through the medium of the hand wheel 14. The piston head B is shown as comprising a head 18 held against movement toward the end of 70 the piston rod A adjacent the throttle 16 by tapering the rod at one end. Mounted upon the piston rod A at the end thereof adjacent the pipe 11 is a disk 20 provided with a plurality of perforations 21. Encircling 75 the piston rod A between the collar 18 and the disk 20 is an inner packing ring 22 of the split type and encircling this packing ring 22 are packing rings 23 and 24 also of the split type, said packing rings 23 and 24 bearing against the wall of the cylinder C. The packing rings 22, 23 and 24 are secured 80 between the head 18 and the disk 20 by means of a nut 25 threaded on the end of the piston rod A adjacent the pipe 11. It will 85 be noted that the perforations 21 of the disk 20 are disposed inwardly of the packing rings 22, 23 and 24 so that the oil under pressure entering the cylinder C will pass through the perforations 21 and bear 90 against the inner face of the packing ring 22 which will result in the expansion of said packing ring and in turn the expansion of the packing rings 23 and 24 so as to effect a tight joint between the packing rings 23 95 and 24 and the cylinder C and prevent the passage of oil by the piston head B to the non-pressure end of the cylinder C.

What I claim is:—

In a piston for oil pump governors, a piston rod, a head fixed on said piston rod in spaced relation to the pressure end of the

piston, a perforated disk slidably mounted on the piston rod at the pressure end of the piston, a split ring encircling the piston rod between the head and perforated disk, said 5 ring having its inner face entirely out of engagement with the disk and disposed throughout its extent outwardly of the perforations of said disk and in spaced relation to the piston rod, a plurality of split metallic packing rings encircling the first named 10 packing ring and having a combined width

equal to the first named packing ring, and means for forcing the perforated disk against the adjacent edges of the packing ring to clamp said rings between the disk 15 and the head.

In testimony whereof, I affix my signature, in presence of two witnesses.

CHARLES W. SHINTON.
